ABSTRACT OF THE DISCLOSURE

A container having regularly arranged recesses in a bottom part is provided with grooves running between the recesses. The depth of the grooves is varied according to the shape of the stones in the recesses to promote ease in the withdrawal of the stones.

Field of the invention

The invention relates to a container for precious stones, particularly for brilliants.

Description of the prior art

When trading brilliants, the stones are placed, without order, into stone envelopes and sold according to their average weight. This is disadvantageous, for example, for goldsmiths and jewelers, in that a quantity of relatively irregular stones, determined according to weight, must be sorted in a time-consuming operation when, for example, a valuable watch is to be surrounded by a circle of like stones.

When using envelopes, stones are readily and uncontrollably lost. There is thus a need to make the selection of stones easier for a store's buyer, as well as for the store's customer, and at the same time to lessen the risk of loss. The solution was found by departing, in this invention, from the idea of selling stones in stone envelopes; rather, the stones are provided in containers, arranged in an orderly manner in accordance with types and/or dimensions, color, and quality.

Summary of the invention

In the present invention, a container having a sealable sliding lid is provided. In the bottom part of the container, recesses are arranged for each stone in a clear, uniform pattern. The invention provides furthermore that grooves are arranged between the individual recesses for the stones; these grooves facilitate the removal of stones, for example, by means of tweezers. Advantageously, the bottom of the groove is located below the rondure of the stone. The sliding lid is advantageously transparent so that the content of the container is visible even if the lid be closed.

Objects of the invention are: to provide a container making the selection of precious stones easier for buyer and customer; and to provide a container allowing the safe storage of precious stones and at the same time render them easily accessible and observable.

Brief description of the drawing

Other objects and many of the attendant advantages of this invention will be readily appreciated as the same becomes better understood by reference to the following detailed description when considered in connection with the accompanying drawings in which like reference numerals designate like parts throughout the figures thereof and wherein:

FIGURE 1 is a partially sectional, lateral view of the embodiment of the invention with its lid pulled out partially;

FIGURE 2 is a top view of FIGURE 1.

2

FIGURE 3 shows, on an enlarged scale, a recess in the bottom part of the container in lateral section with a partly broken-away stone provided therein;

FIGURE 4 is a perspective view of the embodiment.

5 FIGURE 5 corresponds to FIGURE 1, but the lid is in its closing position.

FIGURE 6 is a top view of FIGURE 3.

Description of the preferred embodiment

10 In a container bottom part 1, preferably made of synthetic material, recesses 3 are provided in a regular arrangement, the dimensions of these recesses corresponding to the dimensions of the stones 5 to be placed therein. It is possible to provide units, for example, for 50 or 100 stones, but also for more stones or less stones. It is likewise within the scope of the invention to arrange, in one bottom part, recesses, for example, for two different sizes.

The container is closed by a lid 2, which is preferably constructed as a sliding lid slidable in interlocking guides

20 in the bottom part. As shown in FIG. 1, when the lid is in its closing position, it rests against the bottom part 1 to block the entrances of recesses 3. Thus, stones will not dislodge due to an accidental jolting of the container. A bore 6 is provided in the lid 2, and a bore 6a is in the bottom part of the container. When the lid 2 is pushed in, as in FIGURE 5, the container is closed and the bores 6, 6a are aligned to form a channel through which a wire 9, a cord, or the like is passed. A massive or flat seal 10 secures the container.

25 In order to remove stones more easily, longitudinal and/or transverse grooves 4, 8 are arranged between the recesses, the bottom of these grooves being somewhat below the rondure or level of maximum diameter of the stones so that the removal of stones by means of tweezers

30 is facilitated. The location of the grooves relative to the rondure is shown in the detail views of FIGS. 3 and 6. A recess 7 is provided at an end of the bottom part to facilitate the withdrawal of stacked containers. This recessed end is constructed as a gripping bar.

35 The container of the invention offers many advantages. The stones are in a clear arrangement and visibly provided in the container. The stones are generally classified according to specific dimensions and can be designated by one to x; a goldsmith or jeweler can thus supervise removal with one glance, and can note in time when it is necessary to reorder a stone.

40 The purchase or sale takes place in accordance with the number or size of the stones.

45 For placing repeat orders, a merchant is aware of the stock which is still on hand.

50 It should be understood, of course, that the foregoing disclosure relates to only preferred embodiments of the invention and that it is intended to cover all changes and modifications of the examples of the invention herein chosen for the purposes of the disclosure, which do not constitute departures from the spirit and scope of the invention set forth in the appended claims.

I claim:

60 1. A container simultaneously functioning as a sorting container, sales display box, storage receptacle and transportation safe for a plurality of precious stones comprising a bottom part (1) having regularly arranged recesses (3) of static dimension in its interior, each of said recesses forming a receptacle for a stone, said recesses having a predetermined shape for the holding of correspondingly shaped stones; said bottom part having at least one set of grooves running between said recesses, said grooves having a depth such that they intercept said recesses below the level of maximum dimension of stones held therein; and a lid means (2) mountable to said bottom part and having a closing position wherein said bottom part is closed, said lid means being transparent.

2. A container as claimed in claim 1, further comprising: said lid means and said bottom part each having a bore (6, 6a); said bores being aligned when said lid means is in its closing position, wherethrough a sealed wire may pass.

3. A container as claimed in claim 2, wherein said lid means is a sliding lid (2) and wherein said bottom part has interlocking means along which said sliding lid is slideable into and out of said closing position.

4. A container as claimed in claim 1, especially suited for stacking with at least one other said container of equal external dimensions, said bottom part having an indentation (7) at one end.

5. A container as claimed in claim 4, said one end of said bottom part having the shape of a grip bar.

6. A package simultaneously functioning as a sorting container, sales display box, storage receptacle and transportation safe for a plurality of precious stones, comprising: a bottom part (1) having regularly arranged recesses (3) in its interior, each of said recesses forming a receptacle for a stone, said recesses having a predetermined shape for the holding of correspondingly shaped stones; said bottom part having at least one set of grooves running between said recesses; correspondingly shaped precious stones in said recess; said grooves having a depth such that they intercept said recesses below the level of maximum dimension of said stones; and a lid means (2)

mountable to said bottom part and having a closing position wherein said bottom part is closed, said lid means being transparent.

7. A package of precious stones as claimed in claim 6, said lid means and said bottom part each having a bore (6, 6a); said bores being aligned when said lid means is in its closing position, wherethrough a sealed wire may pass.
